H. H. WEST.

ATTACHMENT FOR CIRCULAR KNITTING MACHINES.

APPLICATION FILED OCT. 15, 1908.

926,629.

Patented June 29, 1909

UNITED STATES PATENT OFFICE.

HARRY H. WEST, OF PLYMOUTH, PENNSYLVANIA, ASSIGNOR OF ONE-HALF TO
WEST, SR., OF PLYMOUTH, PENNSYLVANIA.

ATTACHMENT FOR CIRCULAR-KNITTING MACHINES.

No. 926,629.

Specification of Letters Patent. Patented June 29, 1909.

Application filed October 15, 1908. Serial No. 457,911.

To all whom it may concern:

Be it known that I, HARRY H. WEST, a citizen of the United States, residing at Plymouth, in the county of Luzerne and 5 State of Pennsylvania, have invented certain new and useful Improvements in Attachments for Circular-Knitting Machines; and I do declare the following to be a full, clear, and exact description of the invention, such 10 as will enable others skilled in the art to which it appertains to make and use the same.

This invention relates to an attachment 5 in which a plurality of threads are fed to the needles to produce striped or reinforced work and in which the threads thrown out of work remain attached to the inner side of the tubular fabric.

20 The object of the invention is to provide simple and efficient means for taking care of the threads which are out of work and which, in the continued revolution of the machine become twisted and entangled, tending to 25 draw the fabric up through the cylinder and interfering with the successful work of the needles and they are also liable to draw and distort the loops of the fabric where the threads are attached to it or to break the 30 thread away from the fabric in the case of tender yarn.

Another object of the invention is to provide a device of this character in which the parts are held rigid in relation to each other 35 to prevent spreading thereof by the catching of pieces of the yarn between them, which if the parts are yieldable renders the device eventually inoperative.

With these and other objects in view, the 40 invention consists of certain novel features of construction, combination and arrangement of parts as will be more fully described and particularly pointed out in the appended claims.

45 In the accompanying drawings, Figure 1 is a central vertical section of a circular knitting machine head provided with this improved attachment; Fig. 2 is a top plan view of a portion of a cylinder head showing 50 this attachment applied; Fig. 3 is a front elevation thereof; Fig. 4 is a perspective view of the attachment detached; and Fig. 5 is a transverse section thereof.

In the embodiment illustrated, this improved attachment is secured to the cam

cylinder and is rotated therewith by the ordinary means. The thread feeding device may be of any ordinary form and, as here shown, three threads are employed.

The attachment comprises an L-shaped 60 member 1, the arm 2 of which is apertured to receive a fastening screw for securing it to the cam cylinder and its other arm 3 is bent downwardly to form a depending member 4 which terminates in a lateral extension 5. 65 The bend in the arm 3 is preferably formed diagonally thereof, as shown clearly in Fig. 4, to bring the extension 5 in proper position to receive the thread when applied whereby the lateral extension 5 is arranged to extend 70 in front of the thread guides as 6, and spaced a suitable distance therefrom. This extension 5 is provided with a longitudinally extending groove 7 and the free end thereof is preferably beveled on its upper face to permit the ready insertion of the threads between it and the complementary member 8, now to be described. This member 8 is made of solid unyieldable metal and is superposed on the extension 5 and secured on its 75 inner end thereto by any suitable means with a washer 9 arranged therebetween to space said member 8 and the extension 5 slightly apart to provide for the insertion of the threads. This member 8 is provided on 80 its lower face with a rib 10 which extends longitudinally thereof and is designed to cooperate with the groove 7 in the extension 5 and engage the threads, as 11, which pass between them from the guides 6 and prevent 85 the twisting or entangling of said threads at the outer side or side adjacent to the cam cylinder of said attachment.

It will be understood that any number of threads may extend down the inside of the 90 tube and in consequence of the revolutions of the machine become twisted, three threads only being shown in the form herein illustrated, the threads 11 shown in Fig. 2 being the floating threads and the thread 12 being 100 the thread in operation for the knitting of the fabric. As the fabric feeds down through the cylinder, more yarn is drawn from the bobbins and the strands 11 are fed between the members 5 and 8 and by the co- 105 operating groove and rib formed on the adjacent faces thereof are held separated as shown in Fig. 2 and are prevented from twisting on the outer side of the attachment adjacent the cam cylinder.

From the foregoing description, taken in connection with the accompanying drawings, the construction and operation of the invention will be readily understood without requiring a more extended explanation.

Various changes in the form, proportions and the minor details of construction may be resorted to without departing from the principle or sacrificing any of the advantages of this invention as defined in the appended claims.

Having thus described and ascertained the nature of my invention, what I claim as new and desire to secure by Letters-Patent is:

1. In combination with a circular knitting machine having multiple feed devices, of an engaging device for the floating or inoperative threads comprising superposed parallel members arranged inside the needle row and secured together at their inner ends, one of said members having a groove extending longitudinally of its inner face, and the adjacent member having a rib for co-operation with said groove to prevent twisting or entangling of the threads on one side of said device and a spacing member arranged between said superposed members at the connected ends thereof.
2. In combination with a circular knitting machine having multiple feed devices, of an engaging device for the floating threads comprising rigid superposed parallel members arranged inside of the needle row and secured together at one end, said members carrying on their adjacent faces co-operating means for preventing the twisting of the

threads passing between said members and at one side thereof and a spacing member arranged between said superposed members at the connected ends thereof.

3. An attachment for circular knitting machines comprising an L-shaped member having one arm provided with means for attachment to the machine and the other arm bent downwardly and provided with a lateral extension, a rigid unyieldable member fixed to said extension and spaced therefrom, said extension and member being immovable relatively to each other and provided with co-operating means for preventing the twisting of the threads passing between them at one side thereof.

4. An attachment for circular knitting machines comprising an L-shaped member having one arm apertured for attachment to the cam cylinder and the other arm bent downwardly on a diagonal line and provided with a lateral extension, a rigid unyieldable member fixed to said extension and spaced therefrom and having its free end inclined upwardly and outwardly, said extension having its free end beveled on its upper face, and said members being immovable relatively to each other and provided with co-operating means for preventing the twisting of the threads at one side thereof.

In testimony whereof I have hereunto set my hand in presence of two subscribing witnesses.

HARRY H. WEST
